(57) **CLAIM**

The ornamental design for a noise device, as shown and described.

DESCRIPTION

FIG. 1 is a top, front, right-side perspective view of a noise device;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof;

FIG. 8 is a bottom view thereof;

FIG. 9 is a back, left-side perspective view thereof, shown in use with exemplary environmental subject matter; and, FIG. 10 is a top view thereof.

The evenly broken lines are shown for the purpose of illustrating both parts of the article as well as exemplary environmental subject matter. None of the broken lines form part of the claimed design.

1 Claim, 10 Drawing Sheets
